UNITED STATES PATENT OFFICE.

CURT KUENTZEL, OF AKRON, OHIO, ASSIGNOR TO THE GOODYEAR TIRE AND RUBBER COMPANY, OF AKRON, OHIO, A CORPORATION OF OHIO.

WRAPPING-MACHINE.

1,113,447.

Specification of Letters Patent.

Patented Oct. 13, 1914.

Application filed August 6, 1913. Serial No. 783,431.

To all whom it may concern:

Be it known that I, CURT KUENTZEL, a subject of William II, Emperor of Germany, residing at Akron, in the county of Summit and State of Ohio, have invented new and useful Improvements in Wrapping-Machines, of which the following is a specification.

This invention relates to improvements in devices for wrapping a continuous strip of material about an annular member so that the wrapping is applied in a plane at right angles to the plane of the revolution of the object.

The general object of the invention is to wrap a strip of material about an object such for instance, as a coil of wire or for wrapping a strip of paper about a finished tire, of course, the tire or core in either instance being an annular object. Provision is made for continuously wrapping about an annular object a continuously-fed strip of material and the mechanism by which this object is accomplished forms an essential feature of this invention, the invention embodying a horizontal rotatable shuttle with an open gape revolving about an annular object mounted in a vertical position in order to effect or carry out the winding operation.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the matter herein-after claimed.

In the drawings in which similar reference numerals indicate like parts in the different figures, Figure 1, is a plan view of my improved machine; Fig. 2, is a view in side elevation looking from the lower part of Fig. 1; Fig. 3, is an elevation looking from the right of Fig. 2; and Fig. 4, is a plan view of a shuttle employed.

The mechanism embodied in this machine consists of an L-shaped frame, one member 1 of which is usually arranged at right angles to the other member 2, the latter em-

bodying an open frame provided with legs 3 and 4, and the member 2 is provided with a shelf 5 having a vertical bearing for a purpose to be later described. The frame 2 is preferably fashioned in the form of a parallelogram and is also provided with a transversely-extending pin 6 forming a pivot for an oscillating arm 7 the lower end of which is provided with a pin 8 on which is mounted a roller 9 provided with a concave face. The member 2 is also provided with a bearing 10 (see Fig. 3) the opening in which is arranged in the same horizontal plane as the axis of the pin 6. The member 1 is also provided with a bearing 11 provided with an opening in horizontal alinement with the opening in the member 10 and in these two openings as bearings is mounted a transversely-extending shaft 12, on the outer end of which is mounted the upper end 13 of an oscillating arm 14, the lower end of which is provided with a transversely-extending pin or shaft 15. Extending between the pins 8 and 15 is a connecting bar 16 provided with an opening in which is mounted a manually-operated pin 17. Extending from a cross bar 18 connecting the lower portions of the posts 3 and 4 of the frame 2 and the upper portion of the frame 2 is an arm 18' formed in the arc of a circle and which is provided with a plurality of openings 19 adapted to receive the inner end of the pin 17 so that when the two oscillatory arms 7 and 14 are shifted they may be locked in any pre-determined position through the medium of the pin 17. By this arrangement it will be seen that as the connecting or cross-bar 18 is shifted to left in Fig. 2, it will maintain itself in parallelism with the upper portion of the frame 2 and that the two rollers 9 and 20 will be raised in a true horizontal plane for a purpose to be later described. Mounted on the shaft 12 outside of the arm 14 is a sprocket wheel 21 and mounted on the shaft 15 inside of the roller 20 is a sprocket wheel 22 and connecting these two sprocket wheels is a sprocket chain 23 by which motion is conveyed from the shaft 12 to the roller 20.

The two rollers 9 and 20 having concave peripheries are designated to support some annular object, such for instance as a tire or a coil 24 and in order to shift the vertical position of the latter the oscillatory arms 7

and 14 are oscillated to thereby raise or lower the annular object, and when in a determined position further movement of the two arms is arrested through the medium of 5 the pin 17 engaging in one of the apertures 19 of the curved arm 18.

In order to revolve the annular object supported on the rollers 9 and 20 the following mechanism is employed:—A suitably driven 10 shaft 25 is provided on which a bevel gear 26 is mounted, and fixedly mounted in a bearing in the shelf 5 is a vertical shaft 27 on the lower end of which is a bevel gear 28 adapted to intermesh with the bevel pinion 15 26. The shaft 27 bears a sleeve 32 carrying a worm 30 arranged to mesh with a worm-wheel 31 on the horizontal shaft 12, so as to induce relatively slow rotation of the lateral shaft while the rotation of the shaft 27 is 20 comparatively rapid. Secured to the sleeve 32 is a member 33 of a clutch, and mounted on the shaft 27 is the companion and shiftable member 34 of the clutch, the latter being shafted by a link 35 which is connected 25 with a bell-crank lever 36 operated by a link 37 connected with a foot-treadle 37', by which means clutching engagement between the members 33 and 34 is induced to thereby control the rotation of the worm-wheel 31 30 and the rollers 9 and 20 through the medium of the sprocket-chain 23.

The annular object 24, whatever its nature may be, is supported in its upright position through the medium of a standard 38 projecting upwardly from the frame 2 provided at its upper end with a vertically-adjustable slide 39 from which projects a horizontal arm 40 provided with a head 41 bearing a pair of inclined arms carrying rollers 42 40 adapted to engage the upper portions of the object 24 and hold it during its revolution.

The frame member 2 is provided with a laterally-extending curvilinearly-formed horizontal bracket 43 provided at its marginal portion with a horizontal flange 44 above which extends a polygonally-shaped portion 45. Mounted on the upper face of the member 43 is a ring-shaped member 46 provided with apertures arranged in radial 45 registration with corresponding apertures in the polygonal member 45 and in these sets of bearings are placed the axles of cone-shaped rollers 47 arranged radially with respect to the center of the body of the annular object 24. Mounted at intervals and preferably polygonally arranged on the member 45 are pins 48 on which are mounted flanged rollers 49. The position of these rollers 49 is such that an annular object will 55 run on the broad faces or peripheries of these rollers 49 and they are so arranged to form a combined track or running surface for a shuttle carrier, to be described. One of the rollers in the set or series of rollers just 60 described and denominated in the drawings 65

by the reference numeral 50, is larger than the rest and forms a terminal roller for a purpose to be later described. These rollers 49 and 50 are rotated as follows: Mounted on the upper end of the shaft 27 is a flanged 70 pulley 51 around which runs a belt 52 which passes around the outer faces of the rollers 49 and around the face of the pulley 50 and from thence around a shuttle, (to be described), and back to the pulley 51. One of 75 the rollers 49 and specifically 53 is positioned in spaced relation with respect to the roller 50 and the opening existing between these two rollers serves as a space through which is passed an annular object 24 when 80 set on the rollers 9 and 20.

Mounted to revolve horizontally on the conical rollers 47 is a shuttle-carrier in the form of a broken ring with its under face 70 adapted to run on the rollers and approximately L-shaped in cross-section to provide when positioned a circularly-formed seat for the shuttle. The outer portion 71 of the shuttle-carrier projects laterally to engage the peripheries of the rollers 49 and 50 and 85 be held between the flanges of said rollers which latter serve to hold the shuttle from vertical movement and to constitute guiding means therefor.

The shuttle employed consists of a circularly-formed box 54 provided with upwardly-extending marginal walls 55 and 56. The general form of the shuttle is that of a broken annulus, that is to say, an annulus with a section removed therefrom and with 100 the ends 57 of the annulus closed and the wall 56 interrupted at 58. In this open portion are placed a pair of upright pins or rollers 59 for a purpose to be described. Extending inwardly from the inner wall 56 105 of the shuttle is a plate 60 on which are a plurality of pins 61 around which the continuous strip of material is drawn and constitutes a tension device on the feeding mechanism of the continuous strip of material from the shuttle. The continuous strip of material contained in the shuttle is wound from end to end around the outer face of the inner wall 56 and at each end of 110 said shuttle the material is bent back on itself to constitute a series of folds with the ends or creases thereof approximately at the ends 57 of the shuttle and these folds, designated in the drawings by the reference numeral 63, are laid upon each other and 115 pressed together until the entire containing portion of the shuttle is filled, with the inner end 64 of the continuous strip of material drawn out of the shuttle through the opening and carried inwardly around the tension pins 61 and 59 to the annular object 24.

In operation the annular object 24 is slowly rotated in a vertical plane on the rollers 9 and 20, as already described, and during this revolution the annular object is 120 125 130

guided and held in its vertical position by means of the guiding rollers 42. In order to wind a strip of material 63 about the annular object 24 during its revolution, the 5 loose end 64 is applied to the face of the annular object 24 and as the shuttle 54 revolves, the continuous strip of material is drawn out and applied helically to the annular object 24 in the manner shown in Fig. 10 2 and this operation is continued until the entire surface is covered by at least one layer of the continuous strip of material.

The continuous withdrawal of the strip of material 63 from the interior of the shuttle 15 54 is permitted by the fact that the various folds or layers of the strip are so arranged as to permit their inward withdrawal through the opening 58 in the shuttle wall and as the strip of material is continuous, 20 although folded circumferentially in the shuttle body each layer is freely inwardly removable through the opening 58, the inner folds being withdrawn first and gradually those folds along the outer wall 55 are later 25 removed.

The opening existing between the ends of the shuttle permits the setting of the annular object 24 in place and when the shuttle revolves, it revolves about the center of the 30 body portion of the annular object 24.

I claim:

1. A winding machine comprising in combination a supporting frame, a pair of pivots theron, one of said pivots embodying 35 a rotatable shaft, an arm mounted on each of said pivots, rollers carried on the free ends of said arms, a bar connecting the free ends of said arms, the pivot for one of said rollers consisting of a rotatable shaft, means 40 connecting the first pivotal shaft with one of said rollers for transmitting motion to the latter, said rollers adapted to support and rotate an annular object in a vertical plane, and a revolute shuttle adapted to

place a continuous strip of material helically about said object during its revolution. 45

2. In a machine of the character described the combination with a supporting frame, a pair of pivots thereon one of which embodies a revolute shaft, means to revolve 50 said shaft, an arm secured to each pivot, rollers carried by the free ends of said arms, means to connect the free ends of said arms, means for transmitting motion from said shaft to one of said rollers, said rollers arranged to support a revolute and annular object in a vertical plane, said arms when oscillated adapted to change the vertical position of said object, means to lock said arms in a pre-determined position, and a shuttle 55 carrying a continuous strip of material adapted to wind said strip helically on said annular object during its revolution.

3. The combination in a device of the character described of a supporting frame, 65 a pair of pivots thereon one of which embodies a rotatable shaft, arms mounted on said pivots and arranged to swing in a vertical plane, rollers revolutely mounted on the free ends of said arms, means to connect the 70 free ends of said arms whereby they swing in unison, said rollers adapted to support and permit an annular object mounted thereon to revolve in a vertical plane, means to transmit motion from said shaft to one of 75 said rollers for revolving said object, a circularly-formed shuttle having a section thereof permanently removed and adapted to revolve about said object and wind a continuous strip of material on said object helically during the revolution of the latter. 80

In testimony whereof I have hereunto set my hand in presence of two subscribing witnesses.
